TIME SWITCH FOR ALARM SYSTEMS

Filed March 20, 1924

Patented Feb. 16, 1926.

1,573,152

UNITED STATES PATENT OFFICE.

PATRICK A. FRIEL, OF RICHMOND HILL, NEW YORK.

TIME SWITCH FOR ALARM SYSTEMS.

Application filed March 20, 1924. Serial No. 700,535.

To all whom it may concern:

Be it known that I, PATRICK A. FRIEL, a citizen of the United States, residing at Richmond Hill, in the county of Queens 5 and State of New York, have invented certain new and useful Improvements in Time Switches for Alarm Systems, of which the following is a specification.

This invention relates to electrical circuit closers or switches which, though designed particularly for use in connection with flow alarms, is adapted for more general use and particularly when it is desired that the contact will be made or the circuit 10 closed only after the lapse of a material amount of time after the circuit closing mechanism has been operated or brought into proximity to the normally spaced contacts.

Among the objects of the invention, therefore, is to provide an alarm or signal system for use in connection with water pipes or mains adapted to indicate to any one in authority that a flow of water is taking 15 place, such for instance, as would be the case in the practice of automatic sprinkler systems for buildings or the like, the mechanism being so designed that a momentary excess pressure on the water due to the flow 20 of the same along the mains or because of other conditions will not serve to cause the manifestation of the signal mechanism, but only when or after when a predetermined 25 number of seconds has elapsed. As a result of the improved time mechanism for closing the circuit it follows that a great deal of annoyance due to premature or undesired sounding of the alarm or manifestation of a signal is prevented, but the 30 mechanism is so designed that when there is a real occasion for the sounding of the alarm due to continued pressure or flow 35 of the water the signal will be manifested promptly.

More definitely stated, my invention involves a time switch mechanism including a movable body or carrier with which are associated normally spaced contacts and a movable circuit closing member, such as a 40 body of fluid movable into proximity with the spaced contacts for bridging them as a result of the movement of the body, but the body being so constructed that a material 45 lapse of time is requisite for completion of the circuit after the movement of the circuit closing member, the construction, how-

ever, being that the circuit closing member will return to normal position practically instantaneously following the tilting of the body back to its normal position. 60

With the foregoing and other objects in view the invention consists in the arrangement and combination of parts hereinafter described and claimed, and while the invention is not restricted to the exact details 65 of construction disclosed or suggested herein, still for the purpose of illustrating a practical embodiment thereof reference is had to the accompanying drawings, in which like reference characters designate the same 70 parts in the several views, and in which—

Figure 1 is mainly a side elevation of my improvement applied to a portion of a water main shown in section, and parts of 75 the switch mechanism being shown in section substantially on the line 1—1 of Fig. 2.

Fig. 2 is a vertical sectional detail of the switch mechanism about on the line 2—2 of Fig. 1.

Fig. 3 is an enlarged longitudinal section 80 of the tiltable body or carrier on the line 3—3 of Fig. 2.

Referring now more specifically to the drawings, I show at 10 a joint of a water circulating system having mounted therein a 85 swinging valve 11 which is normally held closed when the water in the system is static, but which is adapted to open toward the right in Fig. 1 under an extensive pressure toward the left, this mechanism 90 being in general similar to that shown in my previous Letters Patent No. 1466,431 issued to me on the 28th day of August, 1923.

Located at any convenient position is 95 a pressure chamber 12 within which is located a fluid tight diaphragm 13 and to one side of which diaphragm fluid pressure is adapted to be conveyed through a pipe 14 leading from the water circulating mechanism from the region of the valve 11. When the valve 11 opens as above indicated 100 the fluid pressure passes through a port 15 and is conveyed through the pipe 14 and acts to flex the diaphragm 13 in a direction away from the water system or downward as shown herein. This pressure chamber and associated parts just described represent any means for physically actuating the movable parts of my improved time switch.

The principal feature of construction is 110 a body 16 of substantially cross shape having longer and shorter ends 16^a and 16^b and

transversely projected arms 16^e arranged at right angles to one another. Secured in any suitable manner in the remote ends of the arms 16^e are tapped a pair of supporting pivots 17 each having a jamb nut 18 while the pivot bears in a bracket 22 for attachment of a lead wire 20 of any suitable signal or other electric circuit. For convenience of construction and simplicity of operation the arms 16^e are bored directly through from the end of one to the end of the other as at 21, the diameter of this bore being relatively small and the posts 17 constitute pivots as they are journaled in bearings or brackets 22 secured on the inside of the opposite side walls of a switch casing 23, the axis of the pivots being horizontal. The end 16^e being the longer and the heavier, the normal position of the body 16 is as shown in Fig. 2 where the heavier end portion thereof rests upon an actuator 24 in the nature of a lever of the first class pivoted at 25 on a support 26 at the bottom of the casing. The end in contact with the body 16 or carrier 16 is the longer and is bent upward so as to insure proper operation of the parts and the normal tendency of the actuator lever to lie as shown in Fig. 2 with its shorter end projected somewhat upward at an inclination from the pivot 25 in contact with a plunger 27 which is slideable in a vertical sleeve 28 and connected at its upper end at 29 to the diaphragm 13. When an excess pressure is developed in the diaphragm or pressure chamber the plunger 27 is forced downward acting upon the shorter arm of the actuator lever and so causing the upward movement of the longer end thereof and the consequent tilting of the body toward the dotted line position of Fig. 2. For convenience in assemblage and reliability in practice the operating parts now being described are preferably connected to a U-shape bracket or frame 30 fixed centrally within the casing 23. A thimble of insulation 31 is shown passing through the casing 23 and tapped into the frame 30 to assist in locking this frame in position and to provide an outlet for the circuit wires 20.

The aforesaid longer and shorter ends of the body or carrier are longitudinally bored at 32 and 33 respectively and with the bores parallel as indicated. The diameter of the bore 32 is preferably somewhat larger than that of the other. That end of the bore 32 that is normally downward is filled with a movable circuit closing member such as a body of mercury 34, and the end of the bore 32 remote from the mercury communicates with the transverse port 21. The bore 33 intersects the port 21 and extends thence onward to about the mid point of the bore 32 and communicates therewith through a short transverse bore 35. It will

thus be seen that the two main bores 32 and 33 overlap each other along their inner end portions.

The operation of the switch may be briefly summarized as follows in view of the mechanism illustrated: When the actuator 24 is moved as above described to tilt the carrier from normal to abnormal position the body of mercury 34 shifts promptly from one end of the bore 32 to the other, going into communication with the transverse port 21. The relative diameters of these parts are so proportioned that the mercury will flow through the port 21 from the bore 32 to the bore 33 in a gradual rate of speed. After a predetermined number of seconds, say nine or ten, the body of mercury or a portion of it will have flowed through the port 21 and filled the end of the bore 33 that is then downward and constitutes an overflow chamber, assuming that the abnormal pressure continues to act upon the diaphragm and the actuator, holding the carrier in this dotted line or tilted position. When, therefore, the then lower end portion of the bore 33 becomes filled up to the transverse port 21 the mercury will flow laterally filling said transverse port as far as the binding posts, making thereby a closed circuit. When, however, the manifestation of the pressure mechanism is more or less momentary or continued too short a time for the alarm mechanism to be manifested, the actuator is held upward correspondingly too short a time for enough mercury to flow through the small port 21 to fill the end portion of the bore 33 to close the circuit. When the carrier or body tilts back again to its normal position as a result of the dropping of the actuator downward, all the mercury that may have passed laterally through the port 21 into the bore 33 will flow promptly back to normal position through the inner end portion of the bore 33 to the transverse connecting port 35 ready for a subsequent operation. It will thus be obvious that there might occur a more or less rapid succession of short pressure impulses in the water system acting upon the diaphragm and the switch actuator without causing the closing of the circuit, this being the result of the quick return of the circuit closing member or mercury back from the temporary pit or chamber 33 following each impulse of the pressure mechanism.

The body or carrier 16 may be made of fiber or any other relatively cheap and durable material and when plugged as shown at the end of the ports the shiftable circuit closing member 34 therein will be retained indefinitely and will always act promptly for the purpose set forth herein. The construction and assemblage of the device are simple and certain of operation.

I claim:

1. In switch mechanism, the combination of a movable fluid-containing member, electrical contact means borne by said fluid-containing member and spaced from each other along a passage way therein, another passage way spaced from the first mentioned passage way, a plurality of spaced passage ways intersecting the first and the second mentioned passage ways, whereof one extends beyond the first mentioned passage way, and the other in substantially opposite direction beyond the second mentioned passage way.
2. In switch mechanism, the combination of a movable fluid containing member, electrical contact means borne by said member and spaced from each other along a passage therein which extends transversely of said member, another passage extending along said member and communicating with the transverse passage to discharge an electrical conducting material thereinto, a third passage communicating with the transverse passage and acting as an overflow and having communication with the second passage to return said material thereinto, the return passage having communication with the second passage at such an angle that when the fluid is discharged from the second mentioned passage into the transverse passage as aforesaid the fluid will pass the opening of the third passage without being discharged thereinto.
3. In switch mechanism, the combination of a movable fluid containing member, electrical contact means borne by said member, a constricted passage along which said means are spaced, a discharge passage arranged to discharge an electrical conducting fluid into the constricted passage, and another passage of larger bore than the constricted passage arranged to act as an overflow for the fluid in the constricted passage and to return the same into the discharge passage, the axes of the constricted passage and of the overflow being in substantially the same plane but said constricted passage being of smaller bore and therefore shallower than said overflow passage the fluid will be drained from said constricted passage before the fluid in the overflow passage has been wholly returned to the discharge passage.
4. In switch mechanism, the combination of a movable fluid containing member, electrical contact means borne by said member, a passage along which said means are remotely spaced, said passage being constricted to retard the flow of a fluid within the same in a direction from one contact toward the other to bridge said contact means, and a pair of other substantially parallel passages intersecting the first passage one of which extends along said member in one direction from the first passage, and the other of which extends in an opposite direction from the first passage, said passages having communication with each other at a point spaced from the first passage, and being of relatively large bore throughout to facilitate the rapid flow of the fluid therethrough.

In testimony whereof I affix my signature.

PATRICK A. FRIEL.
